UNITED STATES PATENT OFFICE

JOHN GODDARD AND RAYMOND ARTHUR CALVERT, OF SMITHS FALLS, ONTARIO,
CANADA, ASSIGNEES TO THE FIRM FROST & WOOD, OF SMITHS FALLS, CANADA

DRAGBAR FOR CULTIVATORS

Application filed June 1, 1928. Serial No. 282,200.

This invention relates to improvements in drag bars for cultivators, and the objects of the invention are to provide a simply constructed and durable device of this description, particularly for application to cultivators.

Another object of the invention is to provide a yielding cultivator tooth, having in view an improvement in the construction and operation, as well as other incidental advantages.

With these and other objects in view, which will readily appear after the nature of the invention is better understood, the 15 same consists essentially in providing in combination a main draw-bar, a tooth carrying standard pivotally connected thereto, a member pivotally mounted in the draw-bar, a coil spring anchored in the main draw-bar and adjustably connected to said member, an auxiliary draw-bar adapted to straddle the coil spring and pivotally associated with the standard and adjustably and pivotally connected to said member.

25 Referring now to the drawings in which like characters of reference indicate corresponding parts in each figure:

Figure 1 is a side elevation of the draw-bar equipment embodying my invention.

30 Figure 2 is a top plan view of Fig. 1.
Fig. 2 is a top plan view of the aux.

Figure 3 is a detail plan view of the auxiliary draw-bar.

Referring now more particularly to the drawings in which a preferred example of the invention is disclosed, 10 designates the main draw-bar, including two side plates 11 and 12, substantially parallel throughout their length except at one end where these side plates are spread apart as at 13, the opposite ends being tapered to form the adjacent end portions 14 and 15, bolted together in any suitable manner. The side plates are also intermediately connected by the bolt 16 and pivotally mounted between the rear ends thereof as at 17 is a standard 18 forwardly curved at its lower end and to which is detachably secured in any well known manner a ground working tool 19.

Also pivotally mounted adjacent the front end of the main draw-bar 10 between the side

members 11 and 12 is a channelled member 20 formed with lugs 21 between which is pivotally mounted in well known manner as at 22 an auxiliary draw-bar 23, the opposite tapering end of which is pivotally connected to a protruding band member 24 rigidly connected at 25 to the standard 18. This band or bent plate member 24 is provided with a plurality of orifices 26 to individually engage with a retaining bolt 27 pivotally supporting the auxiliary draw-bar and enabling it to be adjusted to different positions. This auxiliary draw-bar comprises side plates 28 and 29 tapered as at 30 at one end and bolted together to engage as above mentioned with the plate 24 and also bent inwardly at the opposite end as at 31 and held apart by a suitable washer 32 and secured together by the cross bolt 34. Anchored to the main draw-bar at 33, is one end of the coil spring 35, the other end being connected to a hooked bolt 36 screw threaded to adjustably engage with the member 20 pivotally mounted between the side plates 11 and 12.

From the forgoing it will be seen that the auxiliary draw-bar is not only operatively connected through the plate 24 with the standard 18, but is also pivotally connected to the member 20 between the side plates 11 and 12 of the main draw-bar, and that the auxiliary draw-bar 23 straddles the coil spring.

With the improved construction as above described, an essential object of the invention is attained, in that a maximum lift is provided by retaining the spring actuated mechanism for the standard substantially below the top of the main draw-bar. At the same time the absence of projecting parts above the main draw bar facilitates the attachment of the superstructure without obstruction or requirement of a great deal of clearance.

The member 20, as already described, is substantially channel shaped and provided with spaced lugs on top and a protruding lug 37 therebeneath provided with an eye or opening to adjustably engage with the hooked screw bolt 36 for the coil spring, this bolt being

ing provided with a nut, whereby the spring is readily tensioned or slackened.

The plates of the auxiliary draw-bar are retained together similarly to the main draw-bar by a bolt member 39 which extends between the plates 28 and 29 midway thereof.

Another feature to note is that the coil spring while fitting at one end within the main draw-bar intermediately extends through the side plates of the auxiliary draw-bar and that the travel upwardly of this bar is limited by the strap 24 striking the drag bar sides, while the parts are so arranged that the coil spring always exerts a strong pulling force so that it is not possible for the standard to swing past the point where said force will not be exerted and fail to return to normal operative position and at the same time the standard will always return to normal operating position regardless of whether the standard is working at a depth.

As many changes could be made in the above construction and many apparently widely different embodiments of my invention, within the scope of the claims constructed, without departing from the spirit or scope thereof, it is intended that all matter contained in the accompanying specification and drawings shall be interpreted as illustrative and not in a limiting sense.

What we claim as our invention is:

1. A seeder or cultivator tooth mechanism comprising a main draw bar, a tooth standard pivotally connected to one end of said draw bar, a channel-shaped member formed with spaced and orificed lugs at one extremity and terminating in a solid orificed lug at the other extremity, the said channel-shaped member being pivotally mounted in the opposite end of the main draw bar, a longitudinally extending coil spring adjustably connected to the solid orificed lug at one extremity of the channel-shaped member and anchored to the main draw bar at the end whereon the shank is mounted, a bent plate member embracing the shank, an auxiliary draw bar pivotally and adjustably connected to said plate, and pivotally connected to the spaced and orificed lugs on the channel-shaped member.

2. The invention according to claim 1 in which the bent plate member for tooth carrying standard is U-shaped to embrace the standard and adapted to protrude horizontally, said plate being provided with a plurality of orifices registering individually with orifices in the auxiliary draw-bar and bolt means extending through the orifices to pivotally connect the auxiliary draw-bar to said plate.

3. In a cultivator tooth of the character described, the combination with a main draw-bar formed open and spread at one end and tapered at the opposite end, a tooth carrying standard pivotally connected to the tapered

end of the said main draw bar, a channel-shaped member pivotally mounted on the main draw bar adjacent the open end thereof, the said member being formed with spaced and orificed lugs at the outer extremity thereof or at the extremity adjacent the open end of the main draw bar and a solid orificed lug at the inner extremity thereof, an auxiliary draw bar formed in two spaced and united sections, pivotally connected at one end to the channel-shaped member through the spaced and orificed lugs at the outer extremity thereof, adjustably and operatively connected at the other end to the standard, a longitudinally extending coil spring adjustably connected at one end to the solid orificed lug on the inner extremity of the channel-shaped member, and anchored at the opposite end to the main draw bar, the said spring extending between the sections of the main draw bar and the auxiliary draw bar, a bracing cross-member in the main draw bar substantially midway thereof and a bracing cross-member in the auxiliary draw bar registering therewith, and means for limiting the travel of the standard, auxiliary draw bar and spring.

In witness whereof we have hereunto set our hands.

JOHN GODDARD.

RAYMOND ARTHUR CALVERT.
